UNITED STATES PATENT OFFICE.

MALCOLM L. COSSITT, OF ALAMEDA, CALIFORNIA, ASSIGNOR TO MANIFOLD IMPRESSIONS CORPORATION, OF CARSON CITY, NEVADA. A CORPORATION OF NEVADA.

MANIFOLDING ATTACHMENT FOR TYPEWRITERS.

1,407,933.

Specification of Letters Patent. Patented Feb. 28, 1922.

Application filed June 13, 1921. Serial No. 477,688.

To all whom it may concern:

Be it known that I, MALCOLM L. COSSITT, a citizen of the United States, residing at Alameda, in the county of Alameda and State of California, have invented certain new and useful Improvements in Manifolding Attachments for Typewriters, of which the following is a specification.

My invention relates to that class of attachments for typewriters and other typing machines such, for example, as calculating machines and the like, in which a manifolding ribbon is so associated with the machine as to be readily moved into and out of functional position.

The object of my invention is to provide a manifolding attachment of this class, simple in construction, effective in operation, and which can be readily applied to the machine without appreciable changes or alterations therein.

To this end my invention consists in the novel manifolding attachment which I shall now fully describe by reference to the accompanying drawings, in which—

Fig. 1 is a top plan view, broken, showing the application of my attachment to the platen-carriage of a machine, the manifolding ribbons being shown in functional position.

Fig. 2 is a sectional end view on the line 2—2 of Fig. 1, the dotted lines showing the thrown-back position of the attachment.

Fig. 3 is a section on the line 3—3 of Fig. 2.

Fig. 4 is a broken front elevation looking from the line 4—4 of Fig. 2.

For the sake of a clear understanding, I shall first describe my attachment and then describe its application to a machine and its operation in connection therewith.

1 is a standard having a foot 1'. There are two of these standards, and they are connected by a rod 2. 3 is an arcuate guide member. There are two of these, one being pivotally mounted or journaled at its rear portion, upon the rod 2, near one end thereof, as shown at 2', the other being correspondingly journaled on the rod near its other end.

Each guide member is formed with a plurality of separate, parallel, lengthwise grooves 3'. In each groove is slidably fitted and guided an arcuate ribbon-carrying slide

4, each having a handle 5. The handles are arranged to conveniently overlap, as shown in Figs. 1 and 4, and each is provided with an extension 5', adapted to detachably receive a clip 6 fitted to the end of the strip, section or length of manifolding ribbon 7. The other end of each ribbon is similarly detachably connected with the handle extension of the corresponding slide in the other slotted guide member, so that the ribbons extend, as seen in Fig. 1 in parallel relation, the full length between the corresponding slides at each end of the device and are adapted, for independent, even and uniform movement in an arcuate path.

To secure this uniform movement, each slide 4 has its upper or convex edge formed or provided with a toothed rack 8.

9 is a tubular casing fixed in bracket members 9' secured to or formed with the rear portions of the arcuate grooved guide members 3.

Within this casing 9 is carried a series of concentrically nested, independently rotatable shafts 10, each carrying at each end a pinion 11, with which the racks 8 of the corresponding ribbon-connected pair of slides 4 engage. Figs. 1 and 3.

The application of my attachment to a typing machine will now be described.

In Figs. 1 and 2—12 indicates a part of the frame of the platen-carriage; 13 is the platen; 14 the platen-shaft; 15 the platen-shaft bearings; and 16 the thumb-wheel for turning the platen. 17, in Fig. 1, is the usual main inking ribbon of the machine, and 18 is the index pointer. 19 is the paper guide apron back of the platen. The usual top members of the platen-shaft bearings 15 are removed by taking out its screws, and in place of these top members, the feet 1' of the standards 1 of my attachment are substituted and are secured by the screws 15'. The rod 2 connecting the standards, lies parallel with and above and back of the platen. The grooved guide members 3 when thrown down, follow substantially the arc of the platen.

It will now be seen that by the movement of the slides 4 within the grooves of said guide members 3, the manifolding ribbons 7 may be carried from their upper limit in which they lie in non-functional position along and above the upper part of the

platens, down to their functional position in the line of type-impact, and back again. As their path of movement is substantially or approximately concentric with the curvature of the platen, due to the arcuate guide members in which their carrying slides are mounted, the whole attachment may be applied in close relation to the platen, thereby securing compactness, even in the non-functional position of the ribbons, and also conducting to simplicity of construction, in that more or less complex provision need not be made for an eccentric or distorted path, to secure the proper or accurate position of the manifolding ribbons with relation to the main ribbon and the index pointer, when said manifolding ribbons reach their functional location in the line of type-impact. When, however, it is necessary to change the ribbons, their detachable clips 6 can be conveniently reached by throwing up the guide members 3 about their pivotal connections on the rod 2, thereby elevating the ribbons a distance above the platen, as shown by the dotted lines in Fig. 2.

In a co-pending application, Serial Number 477,062, filed June 13, 1921, I show an attachment of the present type, in which the arcuate ribbon-carrying slides are fitted in arcuate housing members, in which they lie upon and directly in contact with each other, and serve to guide and direct each other in their travel. I find that it is better as furnishing greater accuracy, and giving less friction and possible interference, to slidably fit each slide in its own separate seat, and, for this reason, I show in the present case, as especially adapted for a plurality of slides and ribbons, the arcuate members 3 as positively grooved to form a plurality of separate housing seats in each of which is fitted and guided an arcuate ribbon-carrying slide, so that each pair of slides, carrying its own ribbon, may be operated independently of any other pair, without interference or without any tendency to disturb the others or move them by frictional contact. This form of the arcuate guide members also enables me to provide, in simple manner, for the automatic tensioning of the ribbons as they approach and reach their functional position in the line of type-impact. In the present case this is accomplished by slightly inclining the grooves 3' in the arcuate guide members 3 at an angle to their sides, as shown in Fig. 1, the inclination being outwardly from their upper to their lower ends, in each member, so that said grooves diverge in one member relatively to those in the other member. It will thus be seen that as a pair of slides travels down in the grooves, the members of the pair move in slightly

divergent paths, and are thus adapted, as they approach the lower limit of their travel, to place and hold the ribbon they carry under tension in the line of type impact.

The operation of the attachment may now be briefly described. Ordinarily, when no duplicate copy is required, all the manifolding ribbons lie above and close to the platen and are out of the way. If one duplicate is to be made, one of the handles 5 is grasped and pulled down, thereby carrying one of the ribbons down with a uniform movement at each end, said ribbon following an arcuate path in front of the platen and passing between the paper sheets in the machine, until it reaches its proper position in the line of type-impact. If more copies are to be made, more ribbons are pulled down. Conversely, any one or more ribbons may be raised again.

I claim:—

1. A manifolding attachment for typewriters and the like comprising a pair of spaced, arcuate guide members, each formed with a plurality of parallel longitudinal grooves; means for securing said guide members to the platen-carriage of the machine at each end of the platen; a plurality of arcuate slides fitted and guided, one in each groove of said guide members; means connecting corresponding slides at each end in pairs, whereby each pair moves in unison; and a manifolding ribbon carried by and between the slides of each pair and adapted by their movement to travel in an arcuate path about the platen from and to a functional position in the line of type-impact.

2. A manifolding attachment for typewriters and the like comprising a pair of arcuate, spaced, guide members, each formed with a plurality of parallel longitudinal grooves at an angle to the sides of said guides, the grooves in one guide diverging with relation to those in the other from their upper to their lower ends; means for securing said guide members to the platen-carriage of the machine at each end of the platen; a plurality of arcuate slides fitted and guided, one in each groove of said guide members; means connecting corresponding slides at each end in pairs, whereby each pair moves in unison; and a manifolding ribbon carried by and between the slides of each pair and adapted by their movement to travel in an arcuate, relatively angular path about the platen, from and to a functional position under tension in the line of type impact.

In testimony whereof I have signed my name to this specification.

MALCOLM L. COSSITT
